UNITED STATES PATENT OFFICE.

HENRY KNOX BRYSON, OF FAYETTEVILLE, TENNESSEE.

AXLE.

No. 845,516.

Specification of Letters Patent.

Patented Feb. 26, 1907.

Application filed June 26, 1906. Serial No. 323,471.

To all whom it may concern:

Be it known that I, HENRY KNOX BRYSON, a citizen of the United States, and a resident of Fayetteville, in the county of Lincoln and State of Tennessee, have invented a new and Improved Axle, of which the following is a full, clear, and exact description.

The invention relates particularly to the construction of axle-spindles for vehicles; and the purpose of the invention is to provide a bearing for the hub of a wheel which will not only permit the wheel to turn with a minimum of friction, but which will also provide a cushioned support for the hub, enabling the wheel to have a vertical movement without lost motion, thus tending to render a vehicle to which said axle-spindle is applied easy riding, even upon very rough roads.

20 A further purpose of the invention is to provide a construction of axle-spindle wherein should any accident happen to its cushion-envelop speedy rectification may be made by any person of ordinary intelligence.

25 The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a sectional side elevation of the improved spindle and a section through a hub adapted thereto. Fig. 2 is an outer face view of the outer cap-flange for the spindle. Fig. 3 is an end view of the spindle with the cushion-envelop removed. Fig. 4 is a vertical section taken practically on the line 4-4 of Fig. 1, and Fig. 5 is a section through a portion of the outer cap-flange of the spindle and the cushion-envelop therefor.

40 A represents an axle, and a the spindle therefor, said spindle being an integral portion of said axle. The spindle a may be of any desired cross-sectional shape. For example, it may be circular in cross-section, or it may be rectangular or polygonal. Where the spindle connects with the axle, a flange 10 is integrally formed, the outer face of which flange is straight or smooth. The flange 10 is circular in general contour and is provided at its central portion with a vertical groove 11, extending from top to bottom, as is clearly shown in Figs. 1 and 3.

A removable cap-flange 12 is also provided for the outer end portion of the axle-spindle a, and said cap-flange 12 is similar in construction to the flange 10, integral with the axle. The cap-flange 12 is also provided with a central vertical groove 11^a, extending through from top to bottom, said groove 11^a of the cap-flange 12 corresponding to and being immediately opposite the groove 11 of the integral flange 10 of the axle, as is also shown in Fig. 1. The cap-flange 12 is provided with a central rectangular or polygonal opening 13^a, which receives a corresponding polygonal reduced member 13 at the outer end of the axle-spindle a. After the cap-flange 12 has been placed on the axle-spindle a it is held in position by means of a nut 14 or the equivalent thereof screwed upon an outer threaded member 15, integral with the spindle a.

75 A cylindrical shell 16 is made to surround the spindle a, and said shell, which is open at its ends, extends practically from the fixed flange 10 to the removable cap-flange 12, as shown in Fig. 1, and the said shell 16 is provided at each end at top and bottom with pins 17, and said pins extend into the grooves 11 and 11^a of the flanges 10 and 12, so that the shell, while it cannot turn around the spindle, is free to have vertical movement.

80 In connection with the shell 16 and the spindle a I employ one or more cushions B. When two cushions are employed, as illustrated in the drawings, they are each of segmental form and jointly fit around the spindle a and are in close engagement with the inner face of the shell 16; but it will be understood that a single cushion provided with a bore and receiving the spindle a may be used 90 instead of the two illustrated. I desire it also to be understood that these cushions may be hollow or pneumatic, in which event they are provided with suitable valves 18, which extend out through openings 19 in the cap-flange 12, or the cushion or cushions used may be constructed solid. Preferably rubber is employed in the construction of the cushion, whether it is solid or chambered.

95 The bore of the hub 20 of the wheel C, adapted to the improved spindle, is greater in diameter than the customary bore for a hub, so that the hub 20 of the wheel C may be readily slipped over the shell 16 and will turn freely thereon. In order to reduce friction 110

tion to the utmost, rollers 21 are introduced between the hub 20 and the shell 16, and these rollers may be connected with the shell or may be connected with the hub, as may be found most desirable.

When a spindle of the character described is employed, the wheel turns freely around the spindle, and at the same time the cushion and its accompanying shell permits the wheel to have vertical movement, so as to accommodate itself to irregularities in the road, and in that way the riding of the vehicle is rendered very easy and exceedingly pleasant.

Having thus described my invention, I claim as new and desire to secure by Letters Patent—

1. The combination with the wheel, of the axle provided with the spindle and with an integral flange between the axle and the spindle, said flange having a vertical groove on its outer face, said spindle having a reduced polygonal portion at the end thereof, a cap-flange having a vertical groove on the inner face thereof, a nut threaded onto the end of the spindle for retaining the cap-flange in place, a cylindrical shell of greater diameter than the spindle encircling the same and on which the wheel is journaled, said shell having at the top and bottom of each end pins extending into the grooves whereby to guide the casing, and a hollow cushion encircling the spindle between the shell and said spindle, said cushion being provided with nipples whereby to inflate the same, and the cap-flange being provided with vertical slots for receiving the nipples

2. The combination with the wheel, of the axle provided with a spindle and with an integral flange between the axle and the spindle, said flange having a vertical groove on its outer face, said spindle having a reduced polygonal portion at the end thereof, a cap-flange on the polygonal portion, said cap-flange having a vertical groove on the inner face thereof, a cylindrical shell of greater diameter than the spindle encircling the same, and on which the wheel is journaled, said shell having at the top and bottom of each end pins extending into the grooves whereby to guide the casing, and a hollow cushion encircling the spindle between the shell and said spindle.

3. The combination with the wheel of the axle provided with the spindle and with an integral flange between the axle and the spindle, said flange having a vertical groove on its outer face, a cap-flange on the end of the spindle and provided with a vertical groove on its inner face, a cylindrical shell of greater diameter than the spindle encircling the same, and on which the wheel is journaled, said shell having at the top and bottom of each end thereof pins extending into the grooves whereby to guide the casing, and a cushion encircling the spindle within the shell.

In testimony whereof I have signed my name to this specification in the presence of two subscribing witnesses.

HENRY KNOX BRYSON.
